UNITED STATES PATENT OFFICE

2,581,002

VACUUM CLEANER NOZZLE HAVING
INTERNAL BAFFLES

David R. Creswell, Douglas, Ariz.

Application May 17, 1948, Serial No. 27,472

1 Claim. (Cl. 15—420)

1

This invention comprises novel and useful improvements in a furniture cleaning tool and more specifically pertains to a vacuum cleaner nozzle which is particularly adapted for cleaning the flat surfaces of furniture and the like.

The principal object of this invention is to provide a nozzle or attachment head for vacuum cleaners which will readily clean smooth surfaces with an improved and efficient cleansing action and a more effective use of the vacuum cleaner suction.

The above object is attained in the present invention by providing a vacuum cleaner nozzle or head which has a flat open base divided by upwardly extending partitions into a plurality of air inlet chambers, which at their upper ends communicate freely with a pair of air ducts or passages formed in the lower portion of a transversely extending suction tube which is preferably integrally but may be otherwise rigidly attached to the nozzle or head, which suction tube is designed for removable attachment to a vacuum cleaner hose or the like.

A still further feature of the invention resides in the provision of a vacuum cleaner nozzle or head as set forth in the preceding object, wherein the lower marginal rim of the open ended head is adapted to rest upon the surface to be cleansed and is provided with a plurality of laterally extending notches therethrough to provide air inlet ports for admitting air into the interior of the hollow head and into the air inlet chambers therein with a view to drawing the cleansing inlet air of the attachment directly across and closely adjacent to the surface to be cleansed and into the interior of the nozzle.

Yet another object of the invention resides in the provision of a vacuum cleaner nozzle or head as set forth in the preceding paragraphs, wherein the suction tube is divided by diametrically positioned, longitudinally extending baffles therein into a plurality of segmental shaped ducts or passages, the lowermost of these passages having free and continuous communication with the air inlet chambers of the head, all of the passages having free communication with the source of suction, and the upper passages freely communicating with the lower passages at the end thereof opposite from the source of suction.

These, together with various ancillary features and objects of the invention which will later become apparent as the following description proceeds, are attained by this device, a preferred embodiment of which has been illus-

2

trated by way of example only in the accompanying drawings, wherein:

Figure 1 is a perspective view showing a preferred embodiment of the invention and illustrating its attachment to a portion of a vacuum cleaner suction hose or the like;

Fig. 2 is a vertical sectional view through the improved cleaner nozzle or head forming the subject of this invention;

Figure 3 is a vertical sectional view taken substantially upon the plane of the section line 3—3 of Figure 2 and at right angles to the view of Figure 2; and,

Figure 4 is a fragmentary vertical sectional view taken substantially upon the plane of the section line 4—4 of Figure 2.

Referring now more specifically to the accompanying drawings wherein like numerals designate similar parts throughout the various views, 20 it will be seen that numeral 10 designates generally the improved vacuum cleaner nozzle or head forming the subject of this invention and which is shown as being removably attached to a terminal sleeve 12 with which a hose 14 and 25 forming a part of a conventional vacuum cleaner, not shown, is provided.

The cleaner nozzle or head 10 includes a suction tube 16 which is preferably of circular cross section although not limited to this shape, 30 and which tube is at one end adapted to be slidably engaged upon the terminal sleeve 12 of the hose 14 as shown and indicated in Figure 1 in a known manner. Depending from and preferably formed integral with the tube 16, is a neck portion 18 including parallel downwardly extending walls, see Figure 2, from the lower ends of which extend downwardly, arcuately contoured outer walls 20 and parallel rear and front walls 22 and 24.

40 Preferably, this entire nozzle or head may be formed from a single sheet metal member in various known manners.

As shown best in Figures 3 and 4, the end of the suction tube 16 opposite to that which connects with the terminal sleeve 12 of the vacuum cleaner hose 14, is provided with a detachable closure plate 26 of any desired construction. By this means, air is inducted solely from the open, flat, generally rectangular shaped lower end of the nozzle or head 20, and is delivered by means of the members 12 and 14 to the source of suction such as the motor of the vacuum cleaner or the like.

45 As shown in Figures 2 and 3, the cylindrical interior of the suction tube 16 is divided by dia-

metrically disposed baffles 28 and 30, into a plurality of arcuately shaped longitudinally extending channels. It is to be understood that various numbers of baffles may be employed, depending upon the number of longitudinal conduits, ducts or chambers which it is desired to form within the suction tube 16, to such baffles which are perpendicularly disposed being shown in Figures 2 and 3.

Preferably, the baffle 28 is horizontally disposed while the baffle 30 is vertically disposed, this latter baffle extending down into the hollow portion of the head, between the outer walls 20 thereof, and divides the hollow interior of the head into two equal parts as shown at 32 in Figure 2. As will be further seen, the lower edge of this partition 32 is spaced vertically from the lower open edge or face of the nozzle for a purpose to be later set forth.

As shown best in Figures 2 and 4, the hollow interior of the nozzle or head is further divided by means of downwardly extending partitions 34, which are parallel to each other and to the walls 18, which partitions 34 terminate in arcuately shaped walls 36 likewise terminating in spaced vertical relation to the lower edge of the nozzle or head. The outer walls 20 and the rear and front walls 22 and 24, preferably terminate at their lower edges in a generally rectangular marginal flanged edge as at 38. This edge is adapted to form a snugly fitting, sliding engagement with the surface to be cleansed by the vacuum cleaner nozzle. Throughout various predetermined portions of its perimeter, the flanged edge 38 is provided with a plurality of notches or slots 40 which constitute air inlet ports to admit air into the chambers defined by the portions 32 and 36 within the interior of the vacuum cleaner head. In this connection, it will be noted by reference to Figures 2 and 3, that the various partitions 32, and 36 terminate slightly above the plane of the lower surfaces of the flanges 38, this clearance being indicated at 42 in these figures. This clearance is necessary to establish a restricted communication between the various chambers in the interior of the hollow vacuum cleaner head. As will be seen in Figure 2, the outer walls 20, the arcuate walls 36, and the partition 32, define four chambers, denoted 44, 46, 48 and 50 in the interior of the head, each of these chambers communicating at its upper end with the hollow interior of the suction tube 16. The above mentioned diametrical baffles divide the suction tube into quadrant shaped ducts, passage ways or chambers as indicated at 52, 54, 56 and 58. As will readily be seen, the two chambers 44 and 46 in the head have free communication with the quadrant shaped passage 56, while the chambers 48 and 50 likewise have free communication with the quadrant shaped passage 58. Thus, all four of the air inlet chambers communicate with two of the ducts or passage ways in the suction tube.

As shown in Figure 3, the diametrically disposed baffles terminate inwardly of the ends of the suction tube 16, as shown at 60 and 62. Of course, any suitable dimensions may be employed as desired, but it has been found to be satisfactory in a typical commercial installation, to space the ends of the baffles which are opposite the source of suction, as at 60, a distance of about one quarter of an inch from the closure plate 26 at the end of the tube, while the opposite ends of the baffles are indicated at 62, may be spaced from two to four inches from the suction end of

the tube. Thus, all four of the ducts or passage ways 52, 54, 56 and 58, have free and uninterrupted communication with the common source of suction through the sleeve 12 and vacuum cleaner hose 14, while the two upper passage ways 52 and 54 have a restricted but continuous communication with the lower passage ways 56 and 58, at the opposite end thereof, by means of the clearance between the ends of the baffles at 60 and the cap or closure plate 26.

It will thus be noted that the suction of the vacuum cleaner motor is applied directly to the two lower chambers 56 and 58 and thereby directly to the air inlet chambers, and is likewise applied to the opposite ends of the lower passage ways by means of the upper passages 52 and 54 and connect at the opposite ends thereof.

It is contemplated that this division of the passage area of the suction tube 16 and the application of the suction to both ends of the passage ways 56 and 58, will cause a more even distribution of flow of air from the plurality of air inlet chamber than would a single continuous passage which is not sub-divided by baffles.

From the foregoing, the construction and operation of the device will be readily understood and further explanation thereof is deemed to be unnecessary.

However, since numerous modifications and equivalents will readily occur to those skilled in the art after a consideration of the foregoing specification and accompanying drawings, it is not decided to limit the invention to the exact construction shown and described, with all suitable modifications and equivalents may be resorted to falling within the scope of the appended claim.

Having described the invention, what is claimed as new is:

40 In a vacuum cleaner nozzle, a hollow head curving upwardly from its opposite ends to its mid portion and having a flat, open base, air inlet ports in the lower edge of said base, partitions in said head defining a plurality of air inlet chambers communicating with said ports, a suction tube mounted above said head at its mid portion and communicating with said chambers, longitudinally extending, perpendicular diametrical baffles in said tube defining pairs of upper and lower quadrant shaped chambers, each communicating with a common source of suction, the lower pair of quadrant shaped chambers having direct entry to each of said air inlet chambers and the upper and lower pair of said quadrant shaped chambers having communication at the opposite end of said suction tube from said common source of suction.
